UNITED STATES PATENT OFFICE.

MERRILL I. AKINS, OF BISHOP, AND CHARLES J. MOYER, OF ORCUTT, CALIFORNIA.

FISHING TOOL.

Application filed October 21, 1925. Serial No. 63,878.

This invention relates to that class of devices employed in grappling operations, and particularly pertains to a tool which is especially applicable for use in removing lost 5 under reamer cutters, bailer bottoms, tools, rods, broken drill stems and the like from wells. An object of the invention is to provide a fishing tool by means of which objects lost in wells may be readily grappled 10 and their recovery facilitated, and which is simple in construction and efficient in operation.

Another object is to provide a tool of the above character which includes in its ensemble 15 jaw members adapted to be set in a retracted position and to be automatically released and brought into clamping engagement with the object to be removed from the well on said object being disposed in a position to be engaged by the jaw members.

Another object is to provide a simple and effective trip mechanism for holding the clamping jaw operating mechanism under tension in a retracted position, and adapted 20 to be actuated by contact with the object to be engaged by the clamping jaws to throw the jaw operating mechanism into action.

With the foregoing objects in view, together with such other objects and advantages as may subsequently appear, the invention resides generally in the provision of a plurality of pivotally mounted jaw members in the form of levers, with a spring-pressed wedge member adapted to effect operation of the jaw members to bring them into clamping engagement with an object, and further resides in a trip adapted to be tripped to hold the spring-pressed wedge member in a retracted inoperative position 35 and adapted to be actuated by being brought into contact with the object to be grappled by the jaws to release the spring-pressed wedge member.

The invention further resides in the parts 45 and in the construction, combination and arrangement of parts hereinafter described and claimed, and illustrated by way of example in the accompanying drawings, in which:—

Fig. 1 is a view of the fishing tool as seen in side elevation with parts in vertical section showing the device as set for operation;

Fig. 2 is a detail in section and elevation of the clamping jaws showing them in their advanced position;

Fig. 3 is a detail in section of the trip mechanism as seen on line 3—4 of Fig. 1, showing the same in retracted position.

Fig. 4 is a detail in section of the trip mechanism as seen on the line 4—4 of Fig. 2 showing it in its released position.

Referring to the drawings more specifically, A indicates a shank or stem, the upper end of which is adapted to be engaged with a drill stem whereby the tool may be lowered into a well in the usual manner. Slidably mounted on the shank A is a tapered sleeve B constituting a wedge against which bears a spring C wound around the shank A and seating at its upper end on a collar D 60 affixed to the stem A by set screws E. The spring C is designed to urge the sleeve B downwardly on the shank.

Means are provided for holding the sleeve B in a retracted position with the spring C 70 under tension, which means embodies a catch F consisting of a loose pin mounted in an inclined slot G formed in the shank; the pin F being adapted to be positioned with its outer end projecting a short distance beyond the outer surface of the shank so that the lower edge of the sleeve B will seat thereon, as particularly shown in Fig. 3. The pin F is held against advance movement under pressure of the sleeve B by 80 means of a plunger head H reciprocably mounted in a bore J formed in the lower end portion of the shank; the inner end of the pin F abutting against the side of the plunger head and due to pressure on the pin 90 operating to hold the plunger head against movement. The plunger head is mounted on a stem K of reduced diameter and is beveled at its upper and lower ends as indicated at L and M; the stem K being carried on a 95 push rod N guided in the bore J and projecting below the lower end of shank and terminating in a head O.

A series of clamping jaws P are mounted on the lower end portion of the shank A, 100 each of which jaws is in the form of a lever which extends in substantially a vertical direction and is pivoted at Q with its upper end portion projecting alongside the shank K and curved outwardly as indicated at R; 105 the lower end portion projecting downwardly and terminating beyond the lower end portion of the rod N and being provided near its terminus with a series of upwardly and inwardly inclined spurs S. The clamp- 110

ing jaws are arcuate in cross section at the lower end portions and are collectively encompassed by a cylindrical shell T the lower end of which is open and terminates adjacent the lower end of the clamping jaws. The upper end of the shell T is affixed to the shank A.

In the operation of the invention the device is set by retracting the cone sleeve B in opposition to the spring C and positioning the pin F in the inclined slot G with its outer end portion projecting beneath the lower margin of the tapered sleeve D and positioning the plunger head H so that the inner end of the pin F will abut against the outer cylindrical wall of the latter, as particularly shown in Fig. 3. The outer end of the pin F is rounded and the lower end of the sleeve B seats thereon so that the sleeve D under the urge of the spring C tends to shove the pin F inwardly. Inward movement of the pin F, however, is prevented by reason of its inner end abutting against the plunger head H; the pin F being of such length that when its rounded outer end is positioned to project slightly beyond the outer surface of the shank A into engagement with the sleeve B, the inner end portion thereof will abut against the plunger head H.

When the parts are thus disposed the push rod N will be positioned with its head portion O located adjacent the lower end of the cylindrical shell B and spaced a short distance inwardly from the lower ends of the jaw members P, as shown in Fig. 1. The curved upper end portion R of the clutch members will then be positioned adjacent the lower end of the sleeve B and the lower end portions of the jaw members will be disposed in an outermost position adjacent the inner surface of the shell T in which position they are maintained under the urge of coil springs U bearing between the lower end portion of the shank and the inner faces of the jaw members.

In effecting a fishing operation, the tool is lowered into a well bore casing in the usual manner, being guided therein by the shell T which is of a diameter slightly less than that of the casing so that its lower margin will be positioned close to the inner face of the casing. The lower edge of the cylinder 7 and the lower ends of the jaw members are beveled upwardly and inwardly so as to form a wedge or taper which will facilitate passing of the cylinder over and around the object to be removed from the well bore, and to position the object within the shell and between the jaw members so that the lower end of the push rod will abut thereagainst in such fashion as to hold the rod against movement and permit the shank A to be moved downwardly relative thereto and carry the pin F beyond the lower edge

of the plunger head, whereupon the pin F will be forced inwardly by the pressure of the sleeve B on the outer end thereof so as to release the sleeve B and permit it to move downwardly under the urge of the spring C. Downward movement of the sleeve B effects a wedge action on the upper end portions of the jaw members whereby the latter are rocked on their pivots Q in opposition to the springs U to advance the lower end portion of the jaw members inwardly toward each other and into engagement with the object encompassed thereby so that the object thus engaged may be withdrawn from the well bore together with the fishing tool.

While I have shown and described a specific embodiment of my invention, it is subject to various modifications, and accordingly, I do not limit myself to the exact details of construction and arrangement shown but may resort to such changes as come within the scope of the invention and within the meaning of the appended claims.

I claim:—

1. In a fishing tool, comprising a shank, a plurality of jaw members pivoted on said shank extending below the lower end thereof, said jaw members being provided with upper end portions projecting above their pivotal mountings, a tapered sleeve slidably mounted on said shank extending between the shank and the upper end portions of the jaw members, a spring operable to advance said sleeve, a slideable pin carried by said shank adapted to be positioned to extend beneath said sleeve to hold the latter in its retracted position, a push rod carried by said shank and extending downwardly between said jaw members, means on said push rod for holding said pin against movement under pressure imposed thereon by said sleeve and operable on longitudinal movement of said push rod relative to the shank to release said pin to permit the latter to move under the urge of said sleeve to a position out of engagement with the latter.

2. A fishing tool comprising a shank, a plurality of jaw members pivoted on said shank extending below the end thereof, a cylindrical shell carried by said shank and encompassing the jaw members having an open lower end terminating adjacent the lower ends of the jaw members, said jaw members being provided with upper and end portions projecting above their pivotal mounting, a tapered sleeve slidably mounted on said shank and extending between the shank and the upper end portion of the jaw members, a spiral spring wound on said shank and bearing downwardly on said sleeve, a pin slidably mounted in an inclined slot adapted to be positioned to engage the sleeve when the latter is in a retracted position, a plunger

head reciprocably mounted in a longitudinal bore formed in the lower end portion of said shank operable to control said pin, and a push rod carrying said plunger head and projecting between said jaw members.

3. A fishing tool comprising a shank, formed with an end bore, a push rod longitudinally slidable in said bore projecting below the lower end of said shank, a stem carried by said push rod arranged in said bore, a head on said stem, a pin slidably mounted in an inclined slot in said shank, adapted to be positioned with its inner end abutting against said head, said pin being formed with a rounded outer end portion, a spring-pressed wedge slidably mounted on said shank to be positioned to be engaged by said pin, and a plurality of jaw members pivotally mounted on said shank and depending below the lower end thereof around said push rod, and means for holding said jaw members in a retracted position; said jaw members being provided with upwardly extending end portions arranged to be engaged by said wedge member on advanced

movement of the latter to actuate said jaw members.

4. In a fishing tool, a shank, a spring-pressed slidable sleeve on said shank, a pin engageable with said sleeve to hold it in a retracted position, said pin being arranged to tend to move longitudinally under urge of said sleeve, means for opposing movement of said pin adapted to be actuated to permit advance of the pin under pressure of the sleeve to release the latter, and jaw members operable by advance of said sleeve.

5. In a fishing tool, a shank, a spring-pressed slidable sleeve on said shank, an obliquely arranged slidable pin carried by said shank adapted to be disposed to abut against said sleeve and tending to move under the urge of said sleeve, means for opposing movement of said pin operable to release same to permit movement of said sleeve, and jaw members operable by advance of said sleeve.

CHARLES J. MOYER.
